Inventor:
Harold A. Arnold,
By, Mason & Mason, Attys.

UNITED STATES PATENT OFFICE

HAROLD A. ARNOLD, OF MENOMONEE FALLS, WISCONSIN

CABINET

Application filed September 29, 1928. Serial No. 309,164.

This invention relates to cabinets, and more particularly to cabinets which are expressly designed for use in housing radio frequency receiving sets, although equally useful for other purposes.

One of the objects of the invention is to provide a cabinet of the class referred to in which, when the lid of the cabinet is raised to expose a radio receiving set, the circuit is 10 at the same time closed to render the set operative.

A further object of the invention is to provide a cabinet in which the door is composed of a plurality of parts, some of which are 15 hinged together and are so constructed and arranged that the mere act of lifting the door will cause the parts to be folded in a convenient manner at the top of the cabinet.

A further object of the invention is to provide 20 a cabinet of attractive appearance, of simple design and wherein the front of the cabinet may be exposed for access to the enclosed receiving set by a minimum amount of effort upon the part of the operator.

Other objects, advantages and purposes of 25 the invention will be better understood from the following detailed description, when considered in connection with the accompanying drawing illustrating a preferred form of

the cabinet.

In the drawing:

Fig. 1 is a view in front elevation, illustrating one embodiment of the invention;

Fig. 2 shows the cabinet in plan, with part 35 of the cover removed to disclose the arrangement of the parts therebelow;

Fig. 3 is a cross sectional view, on the line 3—3 Fig. 1;

Fig. 4 is a cross sectional view upon the 40 same plane of section but showing the cabinet cover in open position;

Fig. 5 is a sectional detailed view illustrating the circuit closing means;

Fig. 6 is a similar view, illustrating a portion 45 of the cover resting upon the circuit closing pin, to complete the electrical circuit;

Fig. 7 is a plan view of Fig. 5;

Fig. 8 is a sectional, detailed view illustrating 50 how one of the movable parts of the cabinet lid is guided; and

Fig. 9 is a similar view taken at right angles to Fig. 8.

The cabinet consists of a bottom portion 8, which may be supported upon suitable feet 9, and is provided with sides 12, a back 11, and 55 a top 10, which latter is shown as hingedly connected to the back of the cabinet 11 by suitable hinges 14.

The movable lid or cover of the cabinet, which may be opened and closed to disclose 60 or conceal the interior thereof, is composed of a panel 16, connected by hinges 17 to the forward edge of the top 10; a panel 18, which is rigidly attached to the panel 16 and at right angles to the latter, and a lower panel 20, 65 connected by hinges 21 to the panel 18. The hinges 17 are attached to the front edge of the top 10 and connect the panel 16 with the top in such manner as to permit the former of these parts to fold down, horizontally, so 70 as to form a continuation of the top which extends when the panel 16 is closed, horizontally, so as to fill the space which would otherwise exist at the front of the top 10. When in closed position, the panel 18 extends 75 downwardly in front of the cabinet, and the panel 20 in line thereof, said panels 18 and 20 constituting when closed the front of the cabinet as shown in Fig. 1.

It will be observed that the cover, constituted by the separate panels 16, 18 and 20, does not extend completely across the front of the cabinet, but only for a portion thereof, leaving outside the panels portions 10^a of the cover. Partitions 22, 22, extend from 85 front to rear of the cabinet and substantially in line with the inner edges of the side extensions of the cover 10. The inner sides of these partitions are provided with diagonal grooves, 23, which receive spring-pressed 90 pins 24, carried by the lower edges of the panel 20, said pins travelling in the grooves as the cover is raised to open position, as shown in Fig. 4, or lowered to closed position, as shown in Fig. 3, serving during such 95 movements of the cover to truly guide the panel 20 so that the same will be confined to movements into and out of closed position and will be prevented from being moved into the cabinet. The panel 18 is provided with 100

a handle 25 which is adapted to be grasped in lifting the cover upward for opening the same or for lowering it to close the front of the cabinet. In these operations it is simply necessary to lift the panel 18 upwardly and the cover will be truly guided in its movements from the position shown in Fig. 3 to that shown in Fig. 4, when it is fully opened, by the movement of spring-pressed pins 24 in the grooves 23. The hinge 21 is preferably a spring hinge, whereby the weight of the panel 20 is in part, at least, counterbalanced as the same is raised from the position shown in Fig. 3 to that shown in Fig. 4.

15 Interiorly of the cabinet are two spring-metal electrical contact making members 28, 29, which are suitably secured to the interior of the top 10, and the member 29 is herein shown as carrying a pin 30, whose upper end 20 extends through a hole 32 and normally projects above the top surface of the cover and is adapted to be pressed downward by the weight of the folding cover when the same is in open position, as shown in Fig. 4, causing the members 29, 28, to engage, thereby completing an electrical circuit through the wires 31, which convey current to the radio receiving apparatus 40, which is herein shown as housed within the cabinet. It will thus 25 be seen that when the cover is raised to fully opened position, the weight of the panels thereof upon the contact making pin 30 will automatically close the circuit for setting the receiving apparatus into operation, thereby 30 obviating the necessity of the operation of a switch; and, conversely, when the cover is moved from open position to closed position, the resilient contact member 29 will move away from the member 28, thereby interrupting 35 the circuit and causing the operation of the radio receiver to be suspended.

It will be noted that the several panels of the cover, 16, 18 and 20, are so connected with each other that they form, in effect, a flexible 40 cover for the front of the cabinet, and through the instrumentality of the guiding grooves 23 and pins 24, the movements of the several parts of the cover from closed to open position, and vice versa, may be effected by a very 45 simple movement as it is only necessary to raise the cover by upward movement applied to the handle 25 to cause the various parts of the cover to open and fold upon the top of the cabinet in the manner as shown in Fig. 4; and, by reverse movement of the handle the parts of the cover are caused 55 similarly to move from the position shown in Fig. 4, to the closed position as shown in Fig. 3.

60 A catch 31, indicated in Fig. 4, serves to fasten the top 10 to the side walls 12 of the cabinet so as to prevent accidental opening movements of the top, at those times when such movement is not desired. This catch 65 may be in the form of a simple bolt or any

other simple fastening device which is applied between the forward, side wings 10a of the top and the sides 12 of the cabinet.

The diagonal grooves 23 are preferably provided with depressions at their upper and lower ends into which the pins 24 are pressed in the two extremes of travel of the panel carrying the pins. These depressions serve as stops for holding the cover against accidental movement when in either of its extreme open or closed positions, but the frictional engagement between the pins and depressions is so slight that only a small amount of force is necessary to dislodge the cover.

Changes may be made in the details of construction, or in the arrangement of the several parts illustrated, without departing from the spirit of my invention, provided such changes fall within the scope of the following claims.

I claim:

1. A cabinet of the class described comprising a body portion, a top having a section removed therefrom, a panel hinged to the front edge of the top, a second panel rigidly secured to the first-named panel and projecting at an angle thereto, a third panel hinged to the free edge of the second panel, and means for positively guiding the third panel into position whereby said panels form a cover for the front of the cabinet.

2. A cabinet of the class described comprising in combination a body portion, a top hinged thereto and having a section of its front edge removed to provide a recess, a cover composed of a plurality of sections, one of said sections being hinged to the top, another section rigidly secured to the first section at an angle thereto and a third section hinged to the second section, pins projecting laterally from the edge of the last named section, and partitions extending transversely of the cabinet and enclosing said cover, said partitions provided with inclined grooves to receive the guiding pins of the last-named section of the cover.

3. A cabinet with a body portion, a top portion, and a cover comprising three panels two of which are pivotally connected, one of said panels having one edge hinged to said top portion, another of said panels extending across the front of the cabinet and guiding grooves and pins between said last named panel and the inner walls of the cabinet whereby said cover is guided into a folded position on the top of the cabinet when opened to expose its contents.

4. A cabinet with a body portion, a top portion having a section removed therefrom, and a cover comprising three panels, one of said panels being pivotally connected with said top portion, the second of said panels being attached to said first panel and projecting at an angle thereto when the cover is in a closed position, a third panel hinged to the free edge of said second panel and ex-

tending across the front of the cabinet when the cover is in a closed position, and means for positively guiding said cover into a folded position above the cabinet.

5 In testimony whereof I have hereunto set my hand this 27th day of September, A. D. 1928.

HAROLD A. ARNOLD.
